UNITED STATES PATENT OFFICE

WERNER LEHMAN, OF SOUTH MILWAUKEE, WISCONSIN, ASSIGNOR TO BUCYRUS-ERIE COMPANY, OF SOUTH MILWAUKEE, WISCONSIN, A CORPORATION OF DELAWARE

TOWER EXCAVATOR

Application filed January 9, 1931. Serial No. 507,621.

My invention relates to new and useful improvements in tower excavators.

The conventional tower excavator is well known in the excavating art, being extensively used on such projects as the levee work along the Mississippi River. It consists in a tall tower, of very open lattice-work, known as the "head tower", and a shorter tower, called the "tail tower". The former contains the machinery for actuating the various ropes hereinafter described.

The head tower machinery includes three winches, for the actuation of the three ropes required. One of these ropes, known as the "track cable", is anchored to the tail tower, and serves to support a travelling carriage, from which a drag bucket is suspended. The second rope, called the "drag rope", is directly connected to the bucket, and serves to pull the bucket towards the head tower. The third rope, known as the "back-haul rope", passes from the head tower to a sheave on the tail tower, and thence back to the carriage, its function being to drag the carriage, and therefore the bucket, away from the head tower.

The bucket is raised out of, or lowered into, the work, by hauling on, or slackening, the track cable. Digging is effected by hauling the drag rope. Dumping is effected by slackening the drag rope, and at the same time raising the track cable. Retracting for a new cut is effected by pulling the back-haul rope.

The foregoing is conventional, and is well known.

But this construction has certain disadvantages which I have overcome; notably that the conventional lattice-work head tower straddles a very large base; so that its very great over-all dimensions, as erected, prevent shipment in any other form than as a great multiplicity of parts, which of necessity must remain unassembled until actually taken into the field to the place where the excavator is to be used. For this lattice-work construction, I have substituted a structural mast that can be shipped in two halves, each completely assembled, so as to require in the field nothing more than mere align-

ment and bolting together, these operations being performed before erection, while the mast is still lying horizontal.

There still remain, however, the disadvantages that the erection, and also the dismantling for removal, of such a mast required the use of a gin pole, which, having no function to perform in the finished structure as erected for use, would be laid aside and very frequently overlooked when the entire structure moved further along the levee. My invention contemplates the use of the gin pole as a strut to the mast; thereby not only saving expense, but also making certain that the gin pole shall not be "lost", as the excavator proceeds along the work.

Accordingly, the principal objects of my invention are:

To provide a relatively simple mast for the head tower of a tower excavator system, in place of the wide-open and complicated lattice-work tower formerly thought necessary.

To provide a combined gin pole and strut, for first assisting in raising the mast to an upright position, and then bracing the mast in that position.

In addition to my principal objects, I have worked out a number of novel and useful details, which will be readily evident as the description progresses.

My invention consists in the novel parts, and in the combinations and arrangements thereof, which are defined in the appended claims; and of which one embodiment is exemplified in the accompanying drawings, which are hereinafter particularly described and explained.

Throughout the description of my invention, the same reference number is applied to the same member or to similar members.

On reference to the drawings, it will be seen that:

Figure 1 is a side elevation, showing the essential parts of the conventional tower excavator, as described above.

Figure 2 is a side elevation, showing my head tower mast, in process of erection.

Figure 3 is a side elevation, showing my

head tower mast, erected and ready for service.

In Figures 2 and 3, I have, for the sake of clearness, omitted various details of construction not essential to my invention.

On reference to Figure 1, it will be seen that the conventional tower excavator has a head tower 10, and a tail tower 11, each being usually on creeping traction, and each 10 being provided with machinery (not shown) for propelling itself.

Besides the machinery for propelling itself, the head tower 10 supports upon its 15 base 12 a relatively widely straddling structural tower 13. The machinery upon the base 12 includes three drums (not shown) for actuating various ropes now to be described.

Rope 14 is the track cable, and runs from 20 one of the said drums over a sheave 15 on the tower 13, and thence to an anchorage 15a at the top of the tail tower. From another of the drums the drag rope 16 runs over a sheave 17 situated at about mid-height on the tower 13, and thence to the bucket 18. From 25 the third drum the back-haul rope 19 runs to a second sheave 20 at the top of the tower 13 thence around a sheave 21 at the top of the tail tower, and thence to an anchorage on the carriage 22.

The carriage 22 is adapted to run on the track cable 14, its position thereon being determined by the actuation of the drag rope 16 and the back-haul rope 19.

It will be readily seen from Figure 1 that 30 the superstructure 13 of the conventional head tower far exceeds, in each of its dimensions, the usual railroad clearance; so that of necessity it must be shipped knocked down. In fact, at each removal from one 40 station to another station remote therefrom, it must be dismantled and shipped in parts, to be rebuilt at the new station. Furthermore, the conventional head towers require 45 considerable auxiliary mechanism, such as very powerful cranes, for erecting them or taking them down for removal; whereas, with my invention, only relatively few and simple auxiliary appliances are necessary for 50 these purposes.

Referring now to Figure 3, in which my head tower is shown in working assembly, it will be seen that there is a base 23, which 55 is mounted on creeping traction, conventionally shown at 24. This base supports machinery (not shown), which actuates the traction and other mechanisms.

Pivotedly supported at 25, is a mast 26, of 60 structural material. This mast has, at its head, brackets supporting two sheaves, 27 and 28. At the rear of the mast, and approximately midway of its height, a sheave 29 is supported on brackets. At the front of 65 the mast, and in position approximately as shown, the mast carries a pair of plates, of

which only the one, 30, on the near side of the mast, is shown, the other being similarly placed on the far side. These plates have a series of aligned holes. Upon the front of the mast is a slideable carriage 31, which is 70 provided with holes for the insertion of pins therethrough and also through any desired hole of plate 30 and its symmetrical companion plate, whereby the carriage 31 may be positioned in any desired one of a number of positions. Carriage 31 carries bearings for a sheave 32.

A short distance above the carriage 31, the mast is provided with a "pilot-house", 33, in which the operator is stationed, and which is 80 provided with the various controls required.

At the back of the mast, and symmetrical- 85 ly placed at each side thereof, are carried two brackets; the near one being shown at 34, and each being provided with a flange 35.

The mast is rearwardly supported by a pair 90 of widely straddling back-legs, symmetrical with respect to the central, vertical, fore-and-aft plane of the head tower, the near one of the back legs being shown at 36. These two back-legs are usually cross braced together, so that they may be raised and positioned as a single unit. Thus they together virtually form an A-frame or strut. In raising the mast, they serve as a gin-pole. Thus they may 95 be regarded as a combined gin-pole and strut, or as a gin-pole-strut. The lower ends of the gin-pole-strut 36 are pivoted on the base at 37, and its upper ends (or head) are forked at 38, for the reception, between the forks, of the flange 35. At the center 63 of each leg of the gin-pole-strut is pivoted an auxiliary strut, the near one being shown at 39, each auxiliary strut having its lower end pivoted at the side of the base 23, opposite 105 the foot of the mast, as at 40.

Guy ropes are anchored at each side of the mast head, the near set being shown at 41, their upper anchorages being at 42, and their lower anchorages 43 being adjacent the near 110 rear corner of the base.

From a drum 44 on the base 23, the back haul rope 45 goes to sheave 27, and thence to the tail tower, its further course being as hereinbefore described in connection with 115 Figure 1.

From drum 46 on base 23, the track cable 47 runs to sheave 28, and thence to an anchorage on the tail tower, as hereinbefore de- 120 scribed.

From drum 48, the drag rope 49 goes to sheave 32, and thence to the bucket, as hereinbefore described.

From a fourth drum (not shown, being 125 hidden by drum 48 in Figure 3) on base 23, a rope 50 runs over sheave 29, thence around sheaves 51 and 52, to an anchorage at the pivot of sheave 51. Sheave 51 is fixed to the mast proper, and sheave 52 is fixed to the carriage 31; so that hauling in or paying out 130

rope 50 will respectively raise or lower the carriage 31.

The method of raising my head tower mast will be understood by the following description, having reference to Figure 2.

The cross section of the mast being relatively small, it will be possible to ship on flat cars even the tallest mast in no more than two sections. Each section can therefore be completely assembled before shipping.

The sections are unloaded upon the ground, moved into alignment, and then bolted together. The floor of the pilot house, and all ladders and platforms are then attached to the mast before raising, in order to make all parts accessible during erection. Certain of the sheaves, frames and bearings may be left to be attached after hoisting.

20 The assembled mast 26 is supported on the ground by any convenient means, such, for example, as is shown with respect to one end, by the ties 53.

25 The base, 23, is then brought up to the mast, into position to allow insertion of the pivot pin at 25, thereby coupling the mast to the base at the pivot upon which it is to stand when erected.

30 The two back legs, 36, are then laid on the base, 23, with their feet in position to be readily pivoted at 40. The two back legs are then joined by the cross braces (not shown) or other elements that unite them into a combined gin-pole and strut. The bridle 57 and sheave 58 are then attached at the peak, and the gin-pole-strut is pivotally pinned at 40. At the same time the mast 26 is fitted with bridles 59 and 60, respectively pivoted to the bracket 34 and to one of the anchorages 42, 40 for the purpose of carrying sheaves 61 and 62 respectively, which are to be used in the erecting.

45 The A-frame is temporarily guyed back by two ropes (not shown), one to each side, such guy ropes being supplied with releasable tensioning tackle, and being properly secured to rigidly anchored "deadmen". These guys are for the purpose of preventing any side-wise motion of the gin-pole-strut during

50 erection.

A rope is then run in any convenient manner as, for instance, the rope 62a, shown in Figure 2, over sheaves 58, 62, 61, and attached to one of the drums as at 44. When drum 44 winds up this rope the gin-pole-strut 36 will be raised against the weight of the mast 26.

55 As initially the mast 26 and the gin-pole-strut 36 are both horizontal and therefore virtually in toggle, it is frequently necessary to initiate the upward movement of the peak 34 of the gin-pole-strut, by jacking or otherwise.

60 When the gin-pole-strut is thus raised to the position shown in Figure 2, the two struts 39 are then footed into position by being

pinned at 37. They are then raised into the position shown in Figure 2, and the pin 63 is inserted, thereby fixing the auxiliary struts 39 and the gin-pole-strut 36 into position as shown in Figure 2. For the operation of raising the auxiliary struts into position, the gin-pole-strut, as temporarily supported by its guy ropes, may be used.

65 Temporary side stays 64 are then fastened to the brackets 34 at the head of the gin-pole-strut, their lower ends being anchored at the anchorages 43.

70 Temporary side guys are attached to the top of the mast, then other ends being attached to "deadmen", properly anchored to the ground. These are for the purpose of sustaining the mast during erection, and preventing the partially erected mast from swinging about to the side. For this purpose it is convenient to supply four guy ropes 80 each running at an angle of about forty five degrees from the direction of the mast. Thus, if the mast head lies to the north, the four guy ropes should run approximately to the four directions: northeast, southeast, northwest, and southwest. All guy ropes used on the job are provided with releasable tensioning tackle. Such guy ropes are shown (unanchored) at 54 and 55, and tensioning tackle is indicated at 56.

75 As the gin-pole-strut 36 and auxiliary struts 39 now form a complete and rigid A-frame, standing in the position shown in Figure 2, the mast may now be erected by winding up the rope 62a on drum 44. During this process the guy ropes described in the preceding paragraph are carefully watched, and are kept properly tensioned, the forwardly extending ropes being payed out and the rearwardly extending ropes being taken in.

80 The mast is thus hoisted to a position very nearly perpendicular to the base 23, and all guy ropes are tightened. The hoisting rope is then removed.

85 A rope is then fastened to the top of the A-frame, and is roved through the sheave 62 at the top of the mast, and attached to one of the drums; or several reaches of rope 62a may be used for this purpose. The temporary side stays 64 are removed. The auxiliary struts 39 are detached from the gin-pole-strut and from its footing at 37, and are temporarily laid aside. The gin-pole-strut is unpinned from its footings at 40. The rope mentioned above then raises the gin-pole-strut out of its footings at 40, and it is drawn back to the rear of the machine, lowered into place and pinned at 37. The back guys attached to the top of the gin-pole-strut are then released, allowing the gin-pole-strut to slant forward to a position such that a slight releasing of the ropes that guy the mast forwardly will allow the flanges 35 to slip into the bifurcated head 38 of the gin-pole-strut,

130

the hoisting bridles having been just previously removed. This connection is then securely bolted.

5 The struts 39 are now footed at 40 and pinned at 63 to the gin-pole-strut.

Guy ropes 41 are then attached as shown in Figure 3.

10 The removing of all temporary cables, bridles, and guy ropes, the reaving of all permanent ropes, and the completion of all 15 unfinished parts, such as the operator's booth 33, or the addition of any bearings and sheaves, will now put the mast in condition for use.

15 It will obviously not be necessary to describe the process of lowering the mast for shipment to a distant station, since it consists merely in an obvious reversal of the foregoing processes.

20 Having now described and illustrated one form of my invention, I wish it to be understood that my invention is not to be limited to the specific form or arrangement of parts hereinbefore described, except in so far as 25 such limitations are specified in the appended claims.

What is claimed is:—

1. In a head tower for a tower-excavator system, the combination of: a base frame; a 30 mast, having its foot pivoted on the frame; a drag-cable sheave, adjustable throughout a range of positions on the mast; a combined gin-pole and strut, pivotable at its one end on the frame, and at its other end on the mast; a second pivot for the gin-pole-strut on the frame near the pivot for the foot of the mast; three winches, respectively serving the track cable, the back haul cable and the drag cable, certain of these winches being adaptable to 40 hoist the mast and the gin-pole-strut; and blocks and tackles for such hoisting.

2. In a head tower for a tower-excavator system, the combination of: a base frame; a mast, having its foot pivoted on the frame; 45 a combined gin-pole and strut, pivotable at its one end on the frame, and at its other end on the mast; a second pivot for the gin-pole-strut on the frame near the pivot for the foot of the mast; three winches, respectively serving the track cable, the back haul cable and the drag, certain of these winches being adaptable to hoist the mast and the gin-pole-strut; and blocks and tackles for such hoisting.

55 3. In a head tower for a tower-excavator system, the combination of: a base frame; a mast, having its foot pivoted on the frame; a combined gin-pole and strut, pivotable at its one end on the frame, and at its other end 60 on the mast; a second pivot for the gin-pole-strut on the frame near the pivot for the foot of the mast; three winches, respectively serving the track cable, the back haul cable and the drag cable, certain of these winches being 65 adaptable to hoist the mast and the gin-pole-

strut; and blocks and tackles for such hoisting, part of the block and tackle for hoisting the mast being supported by the gin-pole-strut.

4. In a head tower for a tower-excavator 70 system, the combination of: a base frame; a mast, having its foot pivoted on the frame; a combined gin-pole and strut, pivotable at its one end on the frame, and at its other end on the mast; a second pivot for the gin-pole-strut on the frame near the pivot for the foot of the mast; means for raising the gin-pole-strut, with its foot stepped by the foot of the mast; said means, cooperating 75 with the gin-pole-strut thus raised, for raising the mast.

5. In a head tower for a tower-excavator system, the combination of: a base frame; a mast, having its foot pivoted on the frame; a combined gin-pole and strut, pivotable at its 80 one end on the frame, and at its other end on the mast; a second pivot for the gin-pole-strut on the frame, near the pivot for the foot of the mast; block-and-tackle means for raising the gin-pole-strut, with its foot 85 stepped by the foot of the mast; said block-and-tackle means cooperating with the gin-pole-strut thus raised, for raising the mast.

6. The method of raising and supporting 90 the mast of the head tower of a tower excavator system, which head tower includes a base frame, a mast, and a combined gin-pole and strut member, this method consisting in: first stepping the mast on the base frame 95 of the head tower; then stepping the combined gin-pole and strut member on the base frame near the foot of the mast; then affixing a block and tackle joining the heads of both mast and gin-pole-strut; then utilizing 100 this block and tackle to raise successively the gin-pole-strut and the mast; then restepping the gin-pole-strut at a point on the base frame 105 remote from the foot of the mast; and then securing the top end of the gin-pole-strut to the mast.

7. In a head tower for a tower-excavator system, the combination of: a base frame; a mast, having its foot pivoted on the frame; a 110 drag-cable sheave, adjustable throughout a range of positions on the mast; a combined gin-pole and strut, pivotable at its one end on the frame, and at its other end on the mast; three winches, respectively serving the track cable, the back haul cable and the drag cable, 115 certain of these winches being adaptable to hoist the mast and the gin-pole-strut; and blocks and tackles for such hoisting.

8. In a head tower for a tower-excavator system, the combination of: a base frame; a mast, having its foot pivoted on the frame; a combined gin-pole and strut, pivotable at 120 its one end on the frame, and at its other end on the mast; three winches, respectively serving the track cable, the back haul cable and the drag cable, certain of these winches being 125 adaptable to hoist the mast and the gin-pole-strut; and blocks and tackles for such hoisting.

130

adaptable to hoist the mast and the gin-pole-strut; and blocks and tackles for such hoisting.

9. In a head tower for a tower-excavator system, the combination of: a base frame; a mast, having its foot pivoted on the frame; a combined gin-pole and strut, pivotable at its one end on the frame, and at its other end on the mast; three winches, respectively serving the track cable, the back haul cable and the drag cable, certain of these winches being adaptable to hoist the mast and the gin-pole-strut; and blocks and tackles for such hoisting, part of the block and tackle for hoisting the mast being supported by the gin-pole-strut.

10. In a head tower for a tower-excavator system, the combination of: a base frame; a mast, having its foot pivoted on the frame; a combined gin-pole and strut, pivotable at its one end on the frame, and at its other end on the mast; means for raising the gin-pole-strut; said means cooperating with the gin-pole-strut thus raised, for raising the mast.

25 11. In a head tower for a tower-excavator system, the combination of: a base frame, a mast, having its foot pivoted on the frame; a combined gin-pole and strut, pivotable at its one end on the frame, and at its other end on the mast; block and tackle means for raising the gin-pole-strut; said block and tackle means cooperating with the gin-pole-strut thus raised, for raising the mast.

12. The method of raising and supporting the mast of the head tower of a tower excavator system, which head tower includes a base frame, a mast, and a combined gin-pole and strut member, this method consisting in: first stepping the mast on the base frame of the head tower; then stepping the combined gin-pole and strut member on the base frame; then affixing a block and tackle joining the heads of both mast and gin-pole-strut; then utilizing this block and tackle to raise successively the gin-pole-strut and the mast; and then securing the head of the gin-pole-strut to the mast.

In testimony whereof I affix my signature.
WERNER LEHMAN.
